No. 746,214.

PATENTED DEC. 8, 1903.

M. V. WESTBROOK.
EMBROIDERY SILK FRAME.
APPLICATION FILED MAY 14, 1903.

NO MODEL.

UNITED STATES PATENT OFFICE.

MARY VIRGINIA WESTBROOK, OF HIGHLANDS OF NAVESINK, NEW JERSEY.

EMBROIDERY-SILK FRAME.

SPECIFICATION forming part of Letters Patent No. 746,214, dated December 8, 1903.

Application filed May 14, 1903. Serial No. 157,183. (No model.)

To all whom it may concern:

Be it known that I, MARY VIRGINIA WESTBROOK, a citizen of the United States, residing at Highlands of Navesink, in the county of Monmouth and State of New Jersey, have invented certain new and useful Improvements in Embroidery-Silk Frames; and I do declare the following to be a full, clear, and exact description of the invention, such as will enable

others skilled in the art to which it appertains to make and use the same.

My invention relates to certain new and useful improvements in devices for holding embroidery-silks, fancy-work, sewing material, and the like.

The object of the invention is to produce a holder or frame of this character which is simple and durable in construction, comparatively inexpensive of production, and of great convenience and utility to persons who do sewing and needle-work.

A further object is to provide a frame upon which embroidery - silks, linen and cotton flosses, and other like materials may be held for ready use and prevented from becoming tangled, frayed, or soiled.

With these and other objects in view the invention consists of certain novel features of construction, combination, and arrangement of parts, as will be more fully described, and particularly pointed out in the appended claims.

Figure 1 is a front elevation of my improved silk-frame and work-holder, showing the curtain or cover thrown back. Fig. 2 is a rear elevation of the same with parts in section. Fig. 3 is a vertical sectional view taken on the line 3 3 of Fig. 1. Fig. 4 is a detail horizontal sectional view taken on the line 4 4 of Fig. 1.

Referring to the drawings by numerals, 1 denotes a rigid rectangular frame supported in a vertical position by the feet 2. Said frame comprises the vertical uprights 3 and the cross or connecting bars 4. If desired, the feet 2 may be made removable for convenience in packing and storing the device by forming the lower ends of the uprights 3 with tenons 5, which are adapted to enter mortises formed in the feet, as clearly shown in Fig. 2.

6 denotes a rectangular swinging frame which is pivoted at its center in the rigid

frame 1 by the trunnions 7, formed upon the screws 8, which pass through the uprights or sides of the frame 1 at their central points. Said swinging frame is composed of side and end bars covered by the cloth, fabric, or other material 9. Upon the front face of this swinging frame I secure the holders or guides for the silk, cotton, or linen floss and other like material.

10 denotes a horizontal row of rings arranged across the upper portion of the frame. Said rings are secured upon the fabric covering 9 by the binder 11, which is in the form of a cord or heavy thread, which crosses the row of rings and has its ends secured to the frame 6. At the points where the said binder or strap crosses the rings it is looped or knotted about the same and stitched through the covering or backing 9.

12 denotes a second row of guide or holder rings located below and in line with the upper row. These rings are secured in a similar manner to the covering 9 by the cord or binder 13, as shown in Fig. 4.

14 denotes a strip or band of flexible material arranged horizontally across the frame 6 below the lower row of rings or holders. This band is stitched at intervals corresponding to the width of the rings to form the guide-loops 80 or open pockets 15.

In placing the silk, cotton, linen, &c., in the holders or guides the strands are first passed through the rings 10 and doubled upon themselves. They are then passed beneath the upper portions of the rings 12, over the cross cord or binder 11, and then under the lower portion of said rings, as seen in Fig. 1. By thus securing the strands in the rings or holders 12 it will be seen that the cross cord 90 or binder 11 will hold them up above the fabric, so that they may be separated from each other in order to select a strand for removal for use. The strands after they leave the holders 12 pass through the guide-loops 15.

16 denotes a pocket formed across the lower portion of the front of the frame 6 and designed to receive fancy-work, sewing materials, or appliances of any description.

In order to protect the strands of silk and other material from dust and dirt, I provide a flexible cover or curtain 17, which is secured

across the top end of the frame 6 and is designed to hang down over the front of the same. This curtain may be thrown over and back of the frame 1, as shown by the dotted 5 lines in Fig. 3.

Upon the rear face of the swinging frame 6 I provide the pockets 18 and 19, which are similar to the pocket 16 and which are adapted to hold scissors, thimbles, work-hoops, and 10 other articles of a similar nature.

20 denotes a needle book or holder secured to the back of the frame 6 above the pocket 19. This needle-holder consists of a number of layers of fabric which are sewed together 15 and to the fabric-covering 9.

If it is found desirable, I may dispense with the swinging or adjustable frame 6 and secure the covering or backing 9 upon both sides of the rigid frame 1.

20 The holding devices for the silk, fancy-work, and other articles and the cover 17 will be secured upon the rigid frame in the same manner in which they are secured to the swinging frame, as shown in the drawings.

25 From the foregoing description, taken in connection with the accompanying drawings, the construction and operation of the invention will be readily understood without requiring a more extended explanation.

30 Various changes in the form, proportion, and the minor details of construction may be resorted to without departing from the prin-

ciple or sacrificing any of the advantages of this invention.

Having thus described my invention, what 35 I claim, and desire to secure by Letters Patent, is—

1. A device of the character described, comprising a supporting-frame, a swinging frame mounted therein, silk - holders upon said 40 swinging frame, and a flexible curtain or cover for said swinging frame, substantially as described.

2. A device of the character described, comprising a rigid frame, removable supporting- 45 feet upon said frame, a swinging frame pivoted in said rigid frame, silk and thread holders or guides upon said swinging frame, comprising rows of rings and binders for the same, and a flexible curtain or cover for said swing- 50 ing frame, substantially as described.

3. A device of the character described, comprising a frame, silk and thread holders or guides upon said frame comprising rows of rings and binders for the same, and a flexible 55 curtain or cover for said frame, substantially as described.

In testimony whereof I have hereunto set my hand in presence of two subscribing witnesses.

MARY VIRGINIA WESTBROOK.

Witnesses:

MAUDE C. WESTBROOK,

BERTHA WESTBROOK REID.
